UNITED STATES PATENT OFFICE.

HARRY S. BENJAMIN, OF DETROIT, MICHIGAN, ASSIGNOR TO BENJAMIN MOTOR PRODUCTS COMPANY, OF DETROIT, MICHIGAN, A CORPORATION OF DELAWARE.

INTAKE MANIFOLD FOR INTERNAL-COMBUSTION ENGINES.

Application filed March 27, 1920. Serial No. 369,264.

To all whom it may concern:

Be it known that I, HARRY S. BENJAMIN, a citizen of the United States, residing at Detroit, in the county of Wayne and State 5 of Michigan, have invented certain new and useful Improvements in Intake Manifolds for Internal-Combustion Engines, of which the following is a description.

My invention belongs to that general class 10 of devices interposed between a carburetor and an internal combustion engine, and has for its object the automatic control of a passing medium dependent upon the operation of the engine. To this end it consists in the 15 novel construction, arrangement and combination of parts herein shown and described, and more particularly pointed out in the claims.

The present application is one of a series 20 including my co-pending applications Serial Nos. 347,586 and 362,942.

In the drawings, wherein like reference characters indicate like or corresponding parts—

25 Fig. 1 is a vertical sectional view through the intake and exhaust manifolds of an internal combustion engine, a carburetor being shown in full lines;

Fig. 2 is a section taken substantially on 30 line 2—2 of Figs. 1 and 4;

Fig. 3 is a perspective view of the preferred form of valve;

Fig. 4 is a partial section similar to Fig. 1, showing the valve in a different position;

35 Fig. 5 is a sectional view taken substantially on line 5—5 of Fig. 6, showing a modified form; and

Fig. 6 is a section taken substantially on 40 line 6—6 of Fig. 5.

In the drawings, 1 represents the exhaust 45 manifold of an internal combustion engine, 2 a carburetor, 3 the connection between the carburetor and the intake manifold, and 4 the intake manifold. In the form shown, the intake manifold consists of two branches 5 and 6, the latter being positioned within the exhaust manifold in a position to be heated by the hot gases passing therethrough. The branches 5—5 extend from a point under the bottom of the central passage 7 outward and communicate with the engine intakes 8—8. The branches 6—6 preferably extend across above the upper end of the passage 7 in such manner that the vapor

55 passing therethrough will strike upon the upper wall of the passages and be heated, expanded and vaporized at that point, and thence be directed outward also to the intakes 8—8, where the vapor passing through the branches 5 is intimately co-mingled therewith on the way to the cylinders of the engine. Within the passage 7 is a peculiarly formed valve 9 adapted to be moved upward by the velocity of the passing vapor, depending upon the speed of the engine. The valve 60 is preferably substantially as shown in Fig. 3, being somewhat contracted at the top, as at 10, with side openings 11, a collar 12 at the bottom serving to limit the movement of the valve in either direction. The passage 7 at 65 its upper part is of substantially the same size as the exterior of the valve 9, this contracted portion extending down to a point above the slotted openings 11 and above the reduced or inclined upper face 13. Below 70 this point the passage 7 may be considerably larger if desired, as the valve is guided by extensions 14 upon the upper end thereof, and the remaining side walls of the passage.

The operation of the device as thus described is substantially as follows: With the initial starting of the engine and a partial opening of the throttle, the incoming explosive mixture through the part 3 is directed through the valve 9, escaping through the 75 opening 10, a portion also passing through the slots 11 and upward through the reduced opening 15, thence upward and contacting with the heated wall of the passage 6, as stated. This is a comparatively rich starting 80 mixture, and the engine at this point is not being speeded up, and the entire charge is passed through said opening and in contact with the heated wall, being expanded and thoroughly vaporized and mixed before it reaches the intakes 8. As the engine speeds up, the discharge openings in the valve being too small to take the full and complete charge required, the valve is gradually lifted by the passing mixture, gradually opening 85 the branches 5 and allowing a portion of the mixture to pass by that route to the intakes. At the limit of movement indicated in Fig. 4, the valve occupies the position substantially as therein shown. The said 90 openings or slots 11 are closed by contact with the walls of the passage 7, and the part of the charge that passes through the valve must pass through the reduced opening 10. Obviously this is not sufficient for 95

the demands of the engine, and a portion of the charge passes through the branches 5-5. The liquid hydrocarbon being heavier than air, acquires a greater momentum and passes 5 upward through the opening 10, contacting with the heated walls. The air being lighter, is more readily diverted through the branches 5-5, and is passed to the intakes 8 without heating. At these points the 10 heated, expanded and vaporized hydrocarbon is brought into close and intimate contact with the flowing air and the two are thoroughly and completely commingled, forming an explosive mixture of the best 15 character.

Upon slowing down the engine or idling, when the demands are not so great, the valve 20 may gradually drop downward to such point that the medium passing through the valve 25 and through the branches 5, is just sufficient to supply the demands of the engine, finally being reseated in the position substantially as shown in Fig. 1.

In actual practice I have found my improved device particularly well fitted for 25 use with the heavier hydrocarbons, such for example as kerosene, the latter being thoroughly vaporized and mixed with the air in the manner described.

30 In the form shown in Figs. 5 and 6, the construction is substantially the same, being slightly modified in the connection of the passages from the intake manifold to the intake ports.

35 As here shown, the branches 5-5 instead of leading directly to the intake ports 8, pass up on the opposite side of the exhaust manifold, and are thence bent backwardly, as at 13, across the top of the exhaust manifold 40 and thence downward, as at 14, and at the lower end being connected to the intake port 8. In this form I prefer to employ a venturi or mixing ring 15 at or near the intake port 8 through which the heated charge 45 from the passages 6 is directed, the same escaping through suitable apertures formed in the venturi and mixing with that portion of the charge which has been conducted to the intake ports 8 through the passages 5, 50 13 and 14.

The passing of the portion of the charge through the pipes 5 and to the intake port in the form shown, serves to temper the air without excessively heating the same, which 55 air is then thoroughly mixed with the vapor at a high temperature which passes through

the passages 6. This form of device is particularly effective in the use of heavier hydrocarbon as fuel.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Lette's Patent is:

1. In a device of the kind described, an intake manifold provided with a central chamber and with a plurality of passages leading from the said chamber to the intake ports, in combination with a tubular valve positioned within and movable in said chamber, said valve being provided with a reduced opening at the top and with auxiliary openings at the side thereof, the walls of the chamber being formed to cooperate with the valve, so that the auxiliary openings at the side of the valve are open when the valve is in one position, and said auxiliary openings are closed by the walls of the chamber when the valve is moved to open position, whereby in initially starting the engine a larger portion 85 of the incoming charge will pass through the valve than when the engine is further speeded up.

2. In a device of the kind described, an intake manifold provided with a central chamber which is larger in cross section near the lower part than near the upper part thereof, and provided with a plurality of passages leading from said chamber to the intake ports, in combination with a tubular valve 95 positioned in said chamber with a reduced opening at the top and with auxiliary openings at the side thereof, the parts being arranged with a clearance at the upper part of the valve when it is at its lowermost limit, 100 whereby in initially starting the engine the charge will be conducted through the top and through the auxiliary openings, but upon the vertical movement of the valve the auxiliary openings will be closed. 105

In testimony whereof, I have hereunto signed my name in the presence of two subscribing witnesses.

HARRY S. BENJAMIN.
